FIG. 1

FIG. 2

EDISON G. HULSE INVENTOR.

BY

R. W. Morris

ATTORNEY.

UNITED STATES PATENT OFFICE.

EDISON G. HULSE, OF CUMBERLAND, MARYLAND, ASSIGNOR TO KELLY-SPRINGFIELD TIRE COMPANY, OF CUMBERLAND, MARYLAND, A CORPORATION OF NEW JERSEY.

DESIGN FOR A VEHICLE TIRE.

Application filed May 17, 1924. Serial No. 9,632. Term of patent 7 years.

To all whom it may concern:

Be it known that I, EDISON G. HULSE, a citizen of the United States, residing at Cumberland, in the county of Allegany and State of Maryland, have invented a new, original, and ornamental Design for a Vehicle Tire, of which the following is a specification, reference being had to the accompanying drawing, forming a part hereof.

Figure 1, is a plan view of the design on

a portion of the environment structure—the whole being flattened to better illustrate the detail.

Figure 2, is a cross section through 2—2 of Figure 1, showing the rounded-out aspect of the structure.

I claim:

The ornamental design for a vehicle tire, as shown.

EDISON G. HULSE.
